attorney.

UNITED STATES PATENT OFFICE.

LOUIS F. WRIGHT, OF BROCKTON, MASSACHUSETTS, ASSIGNOR TO WOODARD & WRIGHT
LAST COMPANY, OF BROCKTON, MASSACHUSETTS, A TRUSTEESHIP OF MASSACHU-
SETTS.

SHOE FORM.

Application filed August 20, 1928. Serial No. 300,729.

My present invention relates to shoe forms, and more particularly to a novel and improved construction for connecting the forepart and heel part of said form.

5 An important object of the present invention is the provision of a shoe form which will be strong, rugged, and durable in construction, and which will be possessed of substantially all of the advantages of a solid 10 last.

A further object of the present invention is to provide a forepart having a slot therein of sufficient length and depth to accommodate and conceal a cord, said cord being a 15 flexible connection between the forepart and the heel part, and serving to hold said two parts in yielding engagement when separated.

A further feature of the present invention 20 consists in the provision of a heel part which is of solid wood with the exception of a small recess, said recess being of substantially the size and diameter of the connecting cord and of sufficient depth to enable said cord to be 25 inserted therein and secured to the heel part by suitable attaching means, such as a tack.

A further feature of the invention resides 30 in the fact that the contacting surfaces of said forepart and heel part, with the exception of the said slot in the forepart, are of solid wood.

Another object of the invention is to provide a shoe form wherein the connecting cord is concealed within the forepart, and which 35 shoe form will have the outer appearance of a solid last, excepting for the single line of cut separating the forepart and heel part.

Thus there are no weakened portions in my 40 novel shoe form, and the same will stand considerable hard usage without injury thereto.

A still further feature of my novel shoe 45 form resides in positioning the cord receiving recess in the heel part closely adjacent to the bottom of the contacting face thereof, and in positioning the cord receiving recess in the forepart adjacent to the top of said slot. This permits a wider separation of the two parts than what is possible in any prior 50 form of which I am aware.

Another feature of the invention is the provision of means, on the upper surface of

the heel part, to assist or start the removing of the form from a shoe.

The above and other objects and features 55 of the present invention, details of construction, combination of parts and advantages, will be hereinafter more fully described, pointed out and claimed.

Referring to the drawings, illustrating a 60 preferred embodiment of the invention.

Fig. 1 is a side elevation of my novel shoe form in assembled position;

Fig. 2 is a side elevation of my novel shoe 65 form in assembled position, partly broken away to illustrate the housing and concealment of the cord in the slot in the forepart; and

Fig. 3 is a view of the form in separated 70 position, illustrating the contacting faces of the forepart and heel part.

Referring now to the drawings, for a particular description of the invention, 1 designates the heel part of my novel shoe form, having a contacting face 2, and having 75 therein a recess 3 located adjacent to the central bottom edge of said face 2. In this recess 3 is adapted to be inserted the end 4 of a cord 5, a tack 6, driven from the bottom of the heel part securely holding said end 4 in position.

The cord 5 forms a flexible connecting union or element between the heel part 1 and the forepart 7. Said forepart 7 has a contacting face 8, and approximately midway of said face 8 is a slot 9, having a straight end 10 at its upper portion and a straight end 13 at its lower portion.

Formed in the forepart 7, and located adjacent to the upper end of the slot 9, is a recess 11, adapted to receive the end 15 of the cord 5, a tack 12 inserted from the straight end 10 of the slot 9, securely holding said end 15 in said recess 11, the presence of the straight end 10 facilitating the positioning 95 and driving of said tack 12.

A knob or handle 14 is provided on the upper surface of the heel part 1, to facilitate and assist in withdrawing the heel part of the form from a shoe.

The slot 9 is of sufficient length and depth to accommodate the cord 5 without kinking or crowding the same.

The recess 3, in the heel part 1, is located

just above the straight end 13 of the slot 9, and thus when the forepart and heel part are assembled, there will be no chafing or rubbing, by the forepart, against the cord 5 at this point.

It will be noted, from a glance at the drawing, that the heel part 1 is of solid wood excepting for the presence of the slight recess 3, and that the forepart 7 is of solid wood 10 excepting for the slot 9 and recess 11. The slot 9, being formed approximately midway of the contacting face 8, will not materially detract from the strength of the forepart. Also it will be appreciated that the contacting faces 2 and 8, excepting for the space occupied by the slot 9, are solid wood and when in assembled position, the only apparent distinction between my novel form and a solid last will be the line of cut which forms the 20 faces 2 and 8.

The cord 5 will, of course, constitute means to hold the forepart 7 and heel part 1 in yielding engagement when the parts are separated, as illustrated in Fig. 3.

While my invention has necessarily been described somewhat in detail, it will be appreciated that I may vary the size, shape and

arrangement of parts within reasonably wide limits without departing from the spirit of the invention.

My invention is further described and defined in the form of a claim as follows:

A shoe form divided on a line beginning in front of the highest part and extending rearwardly and downwardly, and a flexible element connecting the forepart and heel part of said form, said forepart having a slot therein of sufficient length and depth to house and conceal said flexible element, the contacting faces of said forepart and heel part being of solid wood with the exception of said slot, one end of said flexible element being attached to said heel part at a point closely adjacent to the bottom of the said slot when said parts are assembled, the other end of said flexible element being attached to the forepart in and closely adjacent to the top of said slot, and means on the upper surface of said heel part to assist in the removal of said heel part from a shoe.

In testimony whereof, I have signed my name to this specification.

LOUIS F. WRIGHT.
